FOLDING CLOSET BED

Filed March 19, 1931

Arthur M. Sorey INVENTOR

UNITED STATES PATENT OFFICE

ARTHUR M. SOREY, OF OKLAHOMA CITY, OKLAHOMA

FOLDING CLOSET BED

Application filed March 19, 1931. Serial No. 523,797.

My invention relates to improvements in folding closet bed adapted to be rolled through a narrow door into a closet but so folded as to occupy a vertical space slightly 5 more than one half of that now required for closet beds.

The principal objects of my invention are:

To provide a device of this character which is new, novel, practical, useful and of evident 10 utility; which is strong, positive in action, durable and reliable; which consists of but few sturdy parts, is easily operated, cannot get out of order easily and is efficient for the purposes for which it is intended; to provide 15 a closet bed with helical spring top coil springs folding up into three sections with a continuous spring top supporting surface; a device in which the said three folding sections are formed from the transverse or 20 short dimension of the bed, the center section being narrow, approximately as wide as twice the thickness of a mattress and adapted to drop down from its normal position in the center of the bed but still remain horizontal; a folding bed in which the two pivoted wider head and foot sections fold up in such vertical spaced position as to form a storage place for a mattress and bed clothes; a device with heavy border wire, hinged to 25 form said sections and said storage place; to provide a folding closet bed having a carriage made of angle iron or tubing and equipped with rubber tired, ball bearing swiveling casters; a device, when folded, 30 which will pass through an average doorway or opening but will be only a little more than one-half as tall as the bed is long, thus permitting the closet space above said folded bed to be utilized for shelves and storage; a device in which the supporting surface may 35 be made with link fabric as well as with helical springs; a device in which multiple spring tension maintains perfect balance of the bed in any position; a folding bed which, on account of its limited height, may be stored under a stairway or attic roof in a space ordinarily wasted; a bed, when unfolded, which is supported at the center by the carriage and at the ends by legs which are positively 40 positioned by automatic actuating means; a

device in which the head board is positioned above the foot end when folded, thus providing protection for the enclosed mattress and bedding; a bed in which the underside of the mattress and springs is exposed to ventilation and sunning, making all parts of the bed accessible for cleaning. 55

With these and other objects in view as will more fully appear, my invention consists in the construction, novel features, and 60 combination of parts hereinafter more fully described, pointed out in the claims hereto appended, and illustrated in the accompanying one-sheet drawings, of which,

Figure 1 is an elevational view of my folding bed showing closed position by dotted lines; Fig. 2 is a side elevation in folded position; Fig. 3 is a partial section of leg actuating means; Fig. 4 is a fragmentary elevation of end of carriage; Fig. 5 is a plan view of bed carriage and Fig. 6 is a perspective view of my bed. 65

Like characters of reference designate like parts in all the figures.

It is understood that various changes in the 75 form, proportion, size, shape, weight and other details of construction, within the scope of my invention may be resorted to without departing from the spirit or broad principle of my invention and without sacrificing any 80 of the advantages thereof, and it is further understood that the drawings are to be interpreted as being illustrative and not restrictive.

Our modern method of living demands that 85 every inch of space in an apartment or home be usable both day and night. In our smaller homes and efficiency apartments, a bedroom that is not convertible to another use during the day is wasted space. In like manner, a 90 den, sewing room, billiard room or library that cannot be utilized for a bed chamber at night is also uneconomic. Setting aside a spare room for guests or infrequent visitors 95 is a waste not to be condoned when space is so costly. My improved folding closet bed, which can be quickly closed, which will enclose, hold and protect the bedding, which can be easily rolled into a limited space under shelves, stairs or attic roof, will make it pos- 100

sible to provide double duty rooms in any home. The simple, efficient, sturdy design of all the parts has made it possible to manufacture this bed at a saving of one-third to one-half of the cost of the so-called door-mounted and roll-away beds.

The preferred embodiment of my invention is shown as follows: The carriage 1 is provided with rubber tired, ball bearing casters 2. Legs 3 are hinged to and support head section 6 and legs 4 in like manner support foot section 7, both of said legs 3 and 4 are properly positioned by means of leg actuator 5. Section 6 is pivoted to inverted U-frame end member 10 of carriage 1 at 8 and section 7 is pivoted similarly at 9. The said U-frame end members 10 are rigidly connected in proper spaced relationship by inwardly bent side frame members 11, said members 10 and 11 are preferably made of tubing but they may be constructed of angle iron. The said side frame members 11 are secured to members 10 by rivets 12, and said members 10 and 11 are further and more rigidly connected by means of riveted angle braces 13. Head section 6 is formed of angle iron frame 14 and foot section 7 of angle iron frame 15 well braced at the corners, the helical coiled bed springs 16 are supported by and connected to said frames 14 and 15 in any suitable manner. The rows of said springs 16 forming the boundary of the bed are properly anchored to heavy border wire 17. Head section 6 and foot section 7 may be made up of any desired number of rows of said springs 16 and any number of springs 16 to the row but narrow midsection 18 will have only two rows 19 of said helical coiled springs, the end pairs of springs 19 being secured to a short section of said heavy border wire 17 between hinges 20 formed on said wire 17. The supporting frame of said narrow midsection 18 is provided with sled runner shaped angle iron end members 23. I provide a U-shaped handle 21 for section 6 and a like handle 22 for section 7 by means of which the bed may be easily folded up or let down, the said handles 21 and 22 also serving as side boards to keep the mattress and bedding in place. Head board member 24 is taller than foot end member 25 as is customary, and in my folding bed said member 24 is made to span the width of the bed when folded so that rubber covered hook 26 on foot section 7 may be used to lock said head board 24 over foot end 25 and securely hold mattress 44 and bedding in folded position. Members 24 and 25 are rigidly riveted to frames 14 and 15 by rivets 27 and 28 respectively. Stops 29 and 30 on frame 10 for frames 14 and 15 respectively hold said frames 14 and 15 in proper vertical position when the bed is folded and locked by hook 26. Legs 3 and 4 are rigidly cross-connected by braced stretchers 31 and 32 respectively. Said legs 3 and 4 are

brought into proper slanting position for rigidly supporting the bed when in open position by leg actuator 5, which consists of rod 33 and tube 34 into which said rod 33 telescopes. Rod 33 is in hinged connection 35 near the center of stretcher 32 and tube 34 is hinged at 36 to side carriage frame 11. The distance between hinge 35 and hinge 36 when the bed is folded, as best seen in Fig. 2, and the length of rod 33 is such that a space 37 is formed between the free end of said rod 33 and the closed end of tube 34, but when the bed is let down the distance between hinges 35 and 36 is less, rod 33 closes up space 37, strikes the closed end of tube 34 and pushes stretcher 32 and attached legs 4 outward into proper position, the same action taking place with legs 3. While I show only one actuator 5 for each pair of legs 3 and 4, more than one for each pair may be provided if deemed necessary.

In order to provide and maintain perfect balance of the bed in any position, heavy tension balance and retrieving springs 38 anchored to side frame members 11 at 39 are secured to the inner ends of frame 14 at 40 and to the inner ends of frame 15 at 41. To insure proper fixed angular relationship in the carriage frame members 10 and 11, I provide cross-brace members 42, riveted to 11 at 46 and at their intersection 47. Coiled tie springs 43 are used to cross-connect the top free end loops of helical springs 16 and 19 and form a resilient spring top supporting surface for mattress 44. Snubber springs 45 maintain the proper relationship between border wire 17 and frame members 14 and 15.

As can best be seen by dotted lines in Fig. 1, when the bed is in folded position, narrow middle section 18 drops down but still retains its horizontal position. Said section 18 is held in suspension at its ends by the short section of border wire 17 hinged at 20. Each of the two rows of helical springs 19 is suspended from its adjoining row of springs 16 by coiled tie springs 43. The top surface of said narrow section 18 thus suspended forms a shelf for contacting the narrow middle fold of mattress 44 and supporting said mattress and other bedding. The heavy border wire 17 forms a fairly rigid end support for section 18 and any undue sagging at the center of said section 18 caused by the resiliency of springs 16, 19 and 43 is halted by the X-brace 42 on side frame members 11. Arrows 49 and 50 indicate the direction and path of travel of sections 6 and 7 about pivots 8 and 9 respectively and arrow 51 shows how legs 4 fold up, against what is the bottom side of frame 7, when said frames 6 and 7 are locked in closed position by hook 26. The whole bed, including the springs, mattress, pillows and bedding is thus compacted into a space having a thickness of approximately four times that of mattress 44, a height of little

more than one-half the length of the bed and a length equal to the width of the bed. The easy running, swiveling casters 2 facilitate rolling the bed in and out of its storage space 5 and around the room which is to become a temporary bed chamber. The carriage 1 will pass through a comparatively narrow doorway and the inward bent side frames 11, spaced apart a distance equal to 10 the thickness of the folded bed, will permit maneuvering the bed around a door jamb or a sharp corner.

When the bed is to be opened and unfolded, hook 26 is released, sections 6 and 7 are let 15 down by means of the handles 21 and 22, springs 38 holding the sections in perfect balance at any stage. As said sections 6 and 7 approach the horizontal, the free ends of rods 33 telescoping into tubes 34, will seat against 20 the closed ends of said tubes 34 and said rods 33 will push stretchers 31 and 32 with attached legs 3 and 4 into stable position for supporting said sections 6 and 7. In unfolding, middle section 18 will be initially lifted 25 by hinged border wire 17, the horizontal legs of the inner ends of angle frame members 14 and 15 will seat under end angle member 23 of section 18, the sled runner ends of said member 23, as can best be seen in Fig. 4, will 30 slidly contact members 14 and 15 and said section 18 will be raised into proper horizontal alinement with said sections 6 and 7. The small gap 48 between the ends of members 14 and 15, when in horizontal position, 35 will thus be spanned by member 23, thus forming as continuous and rigid a bed as if there were no sections at all. Head board member 24 may be made up in any desired form or design and all exposed parts of the bed may be color enameled or finished in imitation wood. For less expensive beds, angle iron may be used and for better grade beds, round or square tubing may be used for exposed frame parts.

45 Having thus described my invention, what I claim as new and desire to secure by Letters Patent is:

1. In a folding closet bed, in combination, 50 a continuous spring top mattress supporting surface of helical spring top coil springs, means for folding said surface into three sections transversely of the length of said bed, a narrow middle section between two wider end sections, a heavy border wire for said 55 helical spring top, said wire being connected to the peripheral springs of all sections, hinge means on said border wire by which said narrow midde section is suspended in a lowered horizontal position when said end sections 60 are folded up in spaced vertical position.

2. In a folding closet bed, in combination, a carriage having inverted U-shaped end frame members mounted upon casters, pivot means 65 on said U-shaped carriage members for wide

head and foot end sections, inwardly bent side frame members on said carriage for maneuvering said folded bed around a door jamb or sharp corner, a plurality of heavy balance and retrieving springs anchored to said side 70 frame members and adapted to be connected to, and to balance and actuate the inner free ends of the frames of said head and foot sections, a narrow middle section supported by the said inner free ends of said end sections, when said bed is unfolded, sled-runner shaped end members for said narrow section, adapted, when said bed is being unfolded, to seat on and slidably contact the inner free ends of said wide sections and span the gap between the said inner free ends, thus forming a rigid, continuous frame for said bed, coiled bed springs supported by said frame, a heavy border wire and coiled tie spring means for forming a continuous spring top mattress 80 supporting surface, hinge means on said border wire for folding said surface into three sections transversely of the length of said bed, said hinged border wire and coiled tie 85 springs forming means for suspending said narrow middle section in lowered horizontal position when said bed is folded.

In testimony whereof I hereunto affix my signature.

ARTHUR M. SOREY.
